UNITED STATES PATENT OFFICE.

STEPHEN BABINEC, OF SHELBY, MICHIGAN.

SHIP-PROTECTOR.

1,256,638.

Specification of Letters Patent. Patented Feb. 19, 1918.

Application filed August 6, 1917. Serial No. 184,664.

To all whom it may concern:

Be it known that I, STEPHEN BABINEC, a subject of the King of Hungary, residing at Shelby, in the county of Oceana and State 5 of Michigan, have invented certain new and useful Improvements in Ship-Protectors, of which the following is a specification.

This invention relates to certain new and useful improvements in ship protectors.

10 The primary object of the invention is the provision of a protector for ships especially adapted for preventing injury thereto at points adjacent the water line from such projectiles as torpedoes, the device being 15 adapted for ready installation upon a ship and arranged so as not to impede the travel of the ship through the water.

20 A further object of the device is to provide a substantially encircling resilient protector for the hull of a vessel which will withstand the projectiles as well as boats and other objects coming in contact therewith.

25 A still further object of the invention is the provision of an inexpensive buffer device adapted for attachment to ships covering any desired portion of the hull thereof, the same being readily repaired when injured and adding strength and stability to 30 the hull on which it is mounted.

In the drawing forming a part of this application and in which like reference characters designate corresponding parts throughout the several views,

35 Figure 1 is a side elevation of a ship provided with the present device.

Fig. 2 is a horizontal sectional view taken upon line II—II of Fig. 1.

40 Fig. 3 is an enlarged detail vertical sectional view through a portion of the device showing a torpedo in engagement therewith, and

Fig. 4 is a vertical sectional view taken upon line IV—IV of Fig. 3.

45 It will be understood that my invention is applicable to any form of boat, and the same is herein illustrated as attached to the hull 10 of a ship 11, the latter having a deck 12, cabin 13, wireless telegraph apparatus 14, and flues 15 while an operating propeller 50 is illustrated at the stern of the hull as well as a rudder 17.

Broadly considered, the invention consists of a plurality of sectional rails 18 resiliently supported in parallelism upon the hull 10 55 and substantially surrounding the hull adjacent the water line thereof. Resilient mounts 19 are provided for the rails 18, each consisting of a base or cup 20 adapted for attachment to the hull 10 by means of 60 screws 21 or similar devices and having caps 22 telescopically mounted upon the cups with springs 23 arranged therein and engaging both the cup and cap. Side slots 24 are arranged in each cup 20 within which 65 pins 25 inwardly projecting from the cap 22 are slidably arranged while a stem 26 is axially positioned within the cap 22 having the spring 23 mounted thereover.

The rails 18 may be of any desired form 70 but are herein illustrated as diamond shaped in cross section with their sharpened edges 75 positioned outwardly. It will be understood that the springs 23 normally maintain the caps 22 projected, whereby the rails 75 18 are resiliently mounted upon the hull 10.

Each of the rails 18 is formed in three sections, a stern section 28 and oppositely positioned similar side sections 29, the adjacent ends of each section being normally 80 spaced apart, thereby permitting the free individual movement of each section inwardly toward the hull 10 when the rail section is contacted from without.

Forward adjacent ends 30 of the rail section 29 are pointed as illustrated being arranged substantially forwardly of the prow 31 of the hull. With a plurality of the rails 18 arranged upon the hull 10 in different horizontal planes as herein illustrated in 90 Fig. 1 it will be apparent that an oncoming missile such as a torpedo 32 will hit some of the rails 27 and by reason of the inclined sides thereof will be deflected toward the passage between two adjacent rails as best 95 illustrated in Fig. 3 and by reason of the slight space between the adjacent rails the torpedo will be enabled to pass therebetween but will be stopped in its travel and there held between the rails or permitted to drop 100 downwardly in the water without contacting the hull.

It is obvious that any desired number of rails 18 may be employed while the rails are

preferably at as well as above and below the normal water line of the hull.

What I claim as new is:—

In combination with a hull, a plurality of 5 cups outwardly carried thereby, caps slidably arranged upon the said cups, springs arranged between the said caps and cups and inclosed therein, rails arranged in sections

and carried by the outer ends of said caps with sharpened edges outwardly arranged, 10 the forward ends of adjacent sections of the rails being pointed and arranged substantially forwardly of the bow of the hull.

In testimony whereof I affix my signature.

STEPHEN BABINEC.
